UNITED STATES PATENT OFFICE.

HENRY F. KOHLER, OF WHITTIER, CALIFORNIA.

GRAPPLE.

987,242.

Specification of Letters Patent. Patented Mar. 21, 1911.

Application filed March 22, 1909. Serial No. 484,878.

To all whom it may concern:

Be it known that I, HENRY F. KOHLER, a citizen of the United States, residing at Whittier, in the county of Los Angeles and 5 State of California, have invented new and useful Improvements in Grapples, of which the following is a specification.

My invention relates to that class of grapples used in oil-well drilling operations and 10 commonly known as "fishing tools," and the main object thereof is to provide a device that may be lowered into an oil-well casing when a tool or parts of a drilling apparatus have been lost therein, and that 15 will instantly grapple the same irrespective of the size of the object, and enable the operator to quickly and easily bring them to the surface.

Another object is to provide a tool that is 20 automatic in its operation and which will firmly retain in place the object grappled until it is brought to the surface.

A further object is to provide a device that is simple in operation, economical in 25 manufacture, one that has few parts, and that will not get out of order readily.

I accomplish these objects by means of the device described herein and illustrated in the accompanying drawings, in which:—

30 Figure 1— is a central vertical section through my complete tool, a number of the arms removed therefrom for clarity of illustration. Fig. 2— is a side elevation of my complete device with the grapping arms 35 thereof in their open or extended position.

Fig. 3— is a sectional plan view taken on line 3—3 of Fig. 2. Fig. 4— is a detail side elevation of one of the grapping arms showing the method of mounting the tooth-grip- 40 ping dog.

Referring more particularly to the drawings, my device consists essentially of a hollow body 5, preferably a cylindrical tube, which is of a sufficient length to enable the 45 operator to lower the tool into the deepest casings. The lower end of this tube is provided with a bearing shoe 6 rigidly secured thereto, which is designed to strengthen the tube at its lower end. Rigidly secured to 50 tube 5 above the lower end thereof is a steel conical casting 7 held in place thereon by a set-screw 8, and is designed to prevent interference with links 10, which compose the upper members of a plurality of toggles 11, 55 when the device is lowered into or raised out of the casing (not shown). Secured to

tube 5 and directly beneath casting 7 is a collar 12 which is provided with a plurality of apertured bearing lugs 13 equal in number to the pivoted links 10, this collar is held 60 in position by means of a second collar 14 which is rigidly secured directly beneath the same to the tube by means of set-screws. The upper ends of links 10 are pivoted in the bearings 13, and the lower ends are pivotally 65 secured to the upper ends of the grapping arms 15. These arms extend downwardly and are bent at approximately right angles and extend through enlarged aperture 16 formed in the lower end of a mandrel 17, 70 the upper end of the mandrel being cylindrical and extends upwardly into the lower end of tube 5. Each of the grapping arms are pivoted as at 18 in the mandrel and extend downwardly a sufficient distance to enable 75 an object to be gripped thereby. The lower end of each of these arms are provided with a plurality of steel dogs 19 pivoted thereto and provided on their lower faces with serrations 20 as clearly illustrated in 80 Fig. 4 of the drawing. Each of the arms where these dogs are pivoted thereto have a cut-away portion adapted to form a shoul- 85 dered seat 21 for the dogs when they are in the position as illustrated in Figs. 1 and 2 of the drawing. It will be noted by an inspection of Fig. 2 of the drawing that the grapping arms 15 are of different lengths, this is to permit of their being pivoted to the 90 mandrel 17, and to take up as little space as possible.

The operation of my device is as follows: When a tool or other object is accidentally lost in a well during a drilling operation, the apparatus, such as an underreamer, is 95 immediately withdrawn and the grapping tool lowered into the casing, the tool being in the closed position illustrated in Fig. 1 of the drawing. When the lower ends of the grapping arms come in contact with the object sought for, the arms will be forced into approximately the position illustrated in Fig. 2 of the drawing, the steel toothed dogs contacting therewith. When this has been accomplished the tube 5 containing the grapping device secured to the lower end thereof is drawn upwardly and the weight of the grapping arms will exert a downward pull on the toggle and force the teeth of the dogs into a gripped relation with the 100 object, which then may be withdrawn with 105 ease and rapidity.

It will be observed from the foregoing description that I have designed a simple and efficient mechanism, whereby objects or articles lost in oil or other wells may be quickly withdrawn therefrom in a minimum amount of time, and with little or no inconvenience to the operator.

Having described my invention what I claim as new and desire to secure by Letters Patent is:—

- 10 1. A grapple, comprising two members, one of said members being stationary and the other movable, the movable member being journaled in the stationary member, a plurality of grapple arms pivotally secured midway their length to the movable member, the upper end of said arms being pivotally connected to the stationary member, and a plurality of pivoted engaging dogs secured 20 to the lower ends of the grapple arms.
- 15 2. A grapple, comprising a hollow stationary member and a vertically reciprocating mandrel journaled therein, a plurality of grapple arms pivotally secured midway

their length to the said mandrel, the lower end of said arms being provided with pivoted engaging dogs, and a plurality of links pivotally secured to the upper end of the grapple arms and to said stationary member.

3. A grapple, comprising a stationary member and a mandrel reciprocating therein, a plurality of grapple arms pivotally secured midway their length to the mandrel, a plurality of gripping dogs pivotally secured to each of said grapple arms, and a plurality of links, said links being pivotally connected to the upper ends of said grapple arms and their free ends being pivoted to the stationary member.

In witness that I claim the foregoing I have hereunto subscribed my name this 15th day of March, 1909.

HENRY F. KOHLER.
